UNITED STATES PATENT OFFICE.

HERMANN MEYER, OF NEW YORK, N. Y.

REWINDING MECHANISM.

No. 923,549.

Specification of Letters Patent.

Patented June 1, 1909.

Application filed September 26, 1908. Serial No. 454,848.

To all whom it may concern:

Be it known that I, HERMANN MEYER, a citizen of the United States, and a resident of the city of New York, borough of the Bronx, in the county and State of New York, have invented a new and Improved Rewinding Mechanism, of which the following is a full, clear, and exact description.

The invention relates to piano players, self-playing pianos and like instruments, and its object is to provide a new and improved rewinding mechanism controlled from the time lever, and arranged to rewind the note sheet without stopping the motor, and to automatically apply a friction brake as soon as the note sheet is rewound, to hold the note sheet under tension during the next following winding up and while passing over the tracker board for actuating the instrument.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a front elevation of the improvement as applied and with the parts in winding-up position; Fig. 2 is an enlarged cross section of the same on the line 2—2 of Fig. 1; Fig. 3 is an enlarged cross section of the same and showing the parts in position when rewinding the note sheet; Fig. 4 is a front view of the support for the pneumatic; Fig. 5 is an enlarged sectional plan view of the improvement on the line 5—5 of Fig. 1; Fig. 6 is an enlarged front elevation of the time lever for controlling the rewinding pneumatic, part being shown in section. Fig. 7 is a plan view of the valve.

The note sheet A unwinds from the unwinding and rewinding roll B, passes over the tracker board C and winds up on the winding-up roller D. The shaft D' of the winding-up roller D is provided with a gear wheel E adapted to be engaged by a pinion F secured on a shaft G, driven in the usual manner from the motor H, the shaft G being journaled at one end in a bearing I fixed to the support J of the frame of the instrument,

and the other end of the said shaft G is journaled in a bearing I' secured to the movable member K' of a pneumatic K held on the support J. When the pneumatic K is inflated, the pinion F is in mesh with the gear wheel E (see Fig. 2), and when the pneumatic K is deflated, as shown in Fig. 3, then the pinion F is out of mesh with the gear wheel E as the movable member K' is now collapsed and has swung the pinion F out of mesh with the gear wheel E. When the pneumatic E is re-inflated, the pinion F is moved back into mesh with the gear wheel E.

On the shaft G adjacent to the pinion F is secured a friction wheel L in mesh with an intermediate friction wheel N, journaled on a swing arm O, fulcrumed at O' on the frame J' of the rewinding mechanism, and the intermediate friction wheel N is adapted to move in contact with a friction wheel P held on the shaft B' of the rewinding roll B. When the pneumatic K is inflated and the pinion F is in mesh with the gear wheel E, as previously explained, then the shaft G is in a lowermost position, and consequently the intermediate friction wheel N is out of frictional contact with the friction wheel P, and when the shaft G is now driven from the motor H then the roll D is turned, to wind up the note sheet A, the power being transmitted from the shaft G to the shaft D' by the pinion F and the gear wheel E. When the pneumatic K is deflated, as shown in Fig. 3, and the pinion F moves out of mesh with the gear wheel E, then the shaft G is moved to its uppermost position, and in doing so the friction wheel L lifts the intermediate friction wheel N, so that the latter moves in frictional contact with the friction wheel P, and the rotation of the shaft G is now transmitted by the friction wheels L, N and P to the shaft B', to rotate the roll B, with a view to rewind the note sheet A on the roll B and to unwind the same from the roll B. It is understood that by the use of the intermediate friction wheel N the roll B is rotated in the proper direction for the rewinding purpose.

In order to hold the note sheet A under tension while being unwound from the roll B and wound up on the roll D, the following arrangement is made: On the shaft B' of the rewinding roll B is secured a brake wheel Q adapted to be engaged by a brake member

Q' held on the outer surface of the movable member K' of the pneumatic K, so that when the pneumatic K is inflated, as shown in Fig. 2, the brake member Q' is in braking contact 5 with the brake wheel Q, thus braking the roll B and thereby giving tension to the note sheet A, as the latter passes over the tracker board C and is wound up by the roll D. When the note sheet A is rewound, as previously explained, and the pneumatic K is deflated, then the brake member Q' moves 10 out of contact with the brake wheel Q, to allow untrammelled rotation of the rewinding roll B for rewinding purposes, as above explained. 15

The pneumatic K is controlled by the performer manipulating the time lever R, which for this purpose is provided with an arm R' adapted to engage a lateral projection S' on 20 a spring valve S controlling an air admission port T, connected by a flexible tube T' with an air chamber K² formed in the fixed member K³ of the pneumatic K. A diaphragm U separates the air chamber K² from a suction 25 chamber V connected by a channel W with the main suction chamber of the instrument, and a valve X connected with the diaphragm U is adapted to connect the suction chamber V with a port K⁴ opening into the pneumatic 30 K, so as to deflate the same, the valve also controlling a connection between the port K⁴ and the atmosphere, to allow the pneumatic K to open or inflate by the action of its spring whenever the port K⁴ is connected 35 with the atmosphere. Normally the spring valve S closes the port T, when the pneumatic K is inflated as shown in Fig. 2, the suction chamber V then being disconnected from the port K⁴ and the latter being open to 40 the atmosphere. When it is desired to rewind the note sheet A, the operator swings the lever R to the right, past the time graduation, and into the position shown in dotted lines in Fig. 6, so that the arm R' opens the 45 valve S and allows air to pass through the port T and the tube T' into the air chamber K², whereby the diaphragm U is forced outward and the valve X is moved to the position shown in Fig. 3, that is, the port K⁴ is closed 50 to the atmosphere and is connected with the suction chamber V, whereby the air is drawn out of the pneumatic K and the latter collapses. The performer holds the lever R in the position referred to until the note 55 sheet A is completely rewound, and then the performer swings the lever R back, to disconnect the arm R' from the projection S' to allow the valve S to close by its own resiliency. When this takes place the atmospheric air is cut off from the air chamber K², and the diaphragm U returns to normal position, thus shifting the valve X, to disconnect the suction chamber V from the port K⁴ and 60 to connect the latter with the atmosphere, to

allow re-inflation of the pneumatic K, as 65 previously explained.

From the foregoing it will be seen that by the arrangement described the rewinding mechanism is controlled by the time lever R, to rewind the note sheet without stopping the 70 motor H, and when the note sheet is rewound and the lever R is moved back to its legitimate position, the brake mechanism is applied to automatically brake the rewinding roll B, and consequently give the desired tension 75 to the note sheet A while passing over the tracker board C during the use of the instrument for playing purposes.

Having thus described my invention, I claim as new and desire to secure by Letters 80 Patent:

1. A rewinding mechanism for piano players, self-playing pianos and the like, provided with a pneumatic carrying on its movable member driven wheels, one for engagement 85 with the driving means of the winding-up roll and one for engagement with the driving means of the rewinding roll, and a brake mechanism having a brake member on the rewinding roll, and a brake member on the 90 said movable member of the said pneumatic.

2. A rewinding mechanism for piano players, self-playing pianos and the like, provided with a pneumatic under the control of the performer, and driven means mounted on 95 and moving with the movable member of the said pneumatic for alternately driving the winding-up roll and the rewinding roll on inflating or collapsing the said pneumatic, the said movable member braking the rewinding 100 roll when the pneumatic is inflated.

3. A rewinding mechanism for piano players, self-playing pianos and the like, comprising a pneumatic under the control of the performer, a driven shaft journaled on the movable member of the said pneumatic, a wheel on the said shaft, a drive wheel on the rewinding roll, and an intermediate wheel between the said shaft and the said rewinding roll wheel, and moved in engagement with 105 the latter by the shaft wheel on collapsing the said pneumatic.

4. In a piano-player, self-playing piano or like instrument, the combination with the speed governing mechanism and the note 115 sheet winding up and re-winding mechanism, of a pneumatic, means in connection with the pneumatic for controlling the note sheet winding up and re-winding mechanism, an air admission valve in connection with the 120 pneumatic, and a common lever for operating the speed governing mechanism and the valve.

5. In a piano-player, self-playing piano or like instrument, the combination with the speed governing mechanism and the note sheet winding up and re-winding mechanism, of a pneumatic, means in connection with the 125

pneumatic for controlling the note sheet winding up and re-winding mechanism, an air admission valve in connection with the pneumatic, a lever for operating the speed controlling mechanism; and means whereby the moving of the said lever beyond a pre-determined point will operate the valve.

In testimony whereof I have signed my name to this specification in the presence of two subscribing witnesses.

HERMANN MEYER.
